UNITED STATES PATENT OFFICE.

THEODORE F. W. MEYER, OF DETROIT, MICHIGAN, ASSIGNOR TO THE JEWETT RADIO & PHONOGRAPH CO., OF DETROIT, MICHIGAN, A CORPORATION OF MICHIGAN.

DESIGN FOR A RADIODIAL.

Application filed January 2, 1925. Serial No. 11,852. Term of patent 3½ years.

To all whom it may concern:

Be it known that I, THEODORE F. W. MEYER, a citizen of the United States, residing at Detroit, in the county of Wayne and State of Michigan, have invented a new, original, and ornamental Design for Radiodial, of which the following is a specification, reference being had to the accompanying drawing, forming part thereof.

Fig. 1 is a plan view of a radio dial embodying my design.

Fig. 2 is a side elevation thereof.

I claim:

The ornamental design for a radiodial as shown.

THEODORE F. W. MEYER.
